UNITED STATES PATENT OFFICE.

URBAN S. ALZ, OF BALTIMORE, MARYLAND.

SAFETY DEVICE FOR ELEVATORS.

SPECIFICATION forming part of Letters Patent No. 628,260, dated July 4, 1899.

Application filed January 31, 1899. Serial No. 703,992. (No model.)

To all whom it may concern:

Be it known that I, URBAN S. ALZ, a citizen of the United States, residing at Baltimore, in the State of Maryland, have invented certain new and useful Improvements in Safety Devices for Elevators, of which the following is a specification.

This invention relates to an automatic device for elevators to safely arrest or stop the car should it accidentally fall.

The object of the invention is to provide a simple device employing compressed air which may be applied to elevators and which will be automatic in its operation.

In order to make the invention clearly understood, I have shown in the accompanying drawings means for carrying the same into practical effect, without, however, intending to limit my invention to this particular construction, as the same may be embodied in other forms.

Figure 1 is a vertical section through an elevator-car with my improved stop device attached and also shows the stationary car-guides and inclined safety-ways. Fig. 2 is a horizontal section on the line 2 2 of Fig. 1. Fig. 3 is a vertical section on the line 3 3 of Fig. 2. Fig. 4 is a section view on a larger scale, showing the vent-valve carried on the car. Fig. 5 is a perspective view showing the cylinders and the pipe connections therewith.

In the drawings, A designates the elevator-car, movable up and down on stationary vertical guides b b', preferably one at each corner of the elevator-shaft. A frame C is secured to the car, preferably at the bottom, and said frame is provided in the present instance with two compartments d and e, one above the other, and a horizontal guide space or slot f is formed between the said two compartments by plates f' f''. The upper compartment d in the present instance contains two air-cylinders d' and d'', located at one end of the compartment, and the lower compartment e is also provided with two air-cylinders e' and e'', located at the opposite end. The air-cylinders have horizontal position, and each is provided with a piston g, having a stem g', which moves loosely through the head of the cylinder, the fit of the stem through the head being such as to allow the free inlet and outlet of air at that end of the cylinder

whenever the piston moves. Two cross-bars h and i are horizontally movable in the space or slot f and extend from one side to the other 55 of the frame C, and said bars at each end carry a pivoted guide-block j. The sliding cross-bar h has two studs k, which project up through slots l in the upper plate f' and are secured to the piston-stems of the upper 60 cylinders d' d'', and the sliding bar h moves with the pistons. The other sliding cross-bar i also has two studs k', which, however, project down through slots in the lower plate f'' and are secured to the piston-stems of the 65 lower cylinders e' e'', and this bar i moves with said pistons.

The elevator-shaft through which the car travels is provided at opposite sides with inclined safety-ways m m', the lower ends of 70 which are close together and which gradually diverge or spread apart as they extend up. It will be understood, of course, that the inclination of the ways m m', as shown in the drawings, is exaggerated in order to make 75 the feature clear. As here shown, the inclined ways m m' are grooved.

The pivoted guide-blocks j have position in the grooves of the inclined ways m m', and it will be seen that as the car moves up the 80 guide-blocks j and their attached parts will move forward—that is, away from their respective cylinders—and the piston g will thereby be drawn toward the cylinder-heads, and the downward movement of the car will 85 cause the said guide-blocks to move in the reverse direction.

The upper air-cylinders d' and d'' are provided with an air-pipe n, which opens in the end of the cylinder opposite the end having 90 the piston-stem, and said pipe n connects with pipe n'. The lower cylinders e' and e'' are also provided with air-pipes o, arranged like the first-named pipes, which connect with the pipe o'. The pipes o' and n' are connected, and thereby form a complete connection between all the cylinders. 95

The guide-blocks j and piston g coact with the inclined guides in such manner that when the car is moving downward the piston will 100 compress the air that may be in the cylinders, and the resistance of this compressed air will gradually arrest the movement of the pistons and guide-blocks, and the car will conse-

quently be gradually stopped. The invention therefore is operative without the employment of a pump; but in the present instance I have shown an air-compressing pump P as a mere supplemental device.

In the present instance the vertical car-guide b' has a rack q , and a pinion r , which is suitably mounted on the top of the car A , meshes with this rack. The pinion or the shaft on which it is mounted carries a crank s . An air-compressing pump P , secured to the top of the car, has a piston and stem of ordinary construction, and a pitman t connects the piston-stem with the said crank s .

15 An air-pipe u connects the air-pump with the pipe n' , communicating with the cylinders under the car, and a valve v , located in the car, controls the escape of compressed air from the cylinders and the pump.

20 The controlling-valve is shown in section in Fig. 4 and is to be operated by hand; but it is obvious that it might be operated by the foot, and the construction may be varied from that shown. In the present instance 25 the valve consists of a cylinder having a piston w , and a stem projects from the piston and has a presser-knob w' . The interior of the cylinder is provided with a groove x , and stop-lugs y y' limit the movement of said piston.

30 It will be seen that when the piston w is pushed down the compressed air will escape around the piston through the groove x , and air from the cylinders will thereby be released.

35 The object of employing the pump P is to aid in the compression of air in the cylinders, to the pistons of which the slide-bars and guide-blocks j are connected.

40 It is to be understood that the pump is intended to compress air in the cylinders both when the car is ascending and descending.

45 The operation of the device is as follows: Suppose the car to be at the bottom of the shaft and the guide-blocks j in the grooves of the inclined ways m m' . As the car moves upward the guide-blocks j will follow the grooves m m' , and the pistons in all the cylinders being connected to the guide-blocks

50 will gradually move outward or make their full stroke toward the cylinder-heads. At the same time the pump P , by means of the rack, pinion, and pitman, will be forcing air through the pipe u to pipes n' and o' , and thereby charging the cylinders behind the pistons with compressed air. The pump P should be so proportioned with respect to the size of the air-cylinders that said cylinders will become filled with compressed air 55 when the car has reached the top of the shaft. Thus it will be seen that when the elevator is going up the cylinders will all become charged with compressed air.

60 In order for the car to descend, air must be discharged from behind the pistons g in order that the guide-blocks may gradually move toward the center vertical line, and to effect

the proper discharge of the air the valve v has been placed in the pipe u , within easy reach of the person who has charge of the 70 car. By means of this valve v the operator discharges air from the pipe u , which reduces the air-pressure acting on the pistons in the cylinders, and upon such reduction of air-pressure the pistons and guide-blocks will move inward and the elevator will descend, but only as fast as the escaping air will permit. By this construction it will be seen that in order to descend the pressure behind the pistons g must be released to permit the guide-blocks j to move toward each other, and the discharge-groove x in the valve can be made larger or smaller, so the discharge of compressed air may be more or less rapid. It will thus be seen that if the cable supporting 85 an elevator-car should break the compressed air not being able to escape from the cylinders would arrest the movement of the pistons and the sliding bars h i and the guide-blocks j would be held stationary in the grooves of 90 the inclined ways m m' and the elevator thereby stopped. The elevator-car having stopped would remain stationary until air was discharged at the valve v .

95 While I have shown and described a pump to be used in connection with the cylinders, it is obvious that the pump may be dispensed with and reliance placed on the atmospheric air in the cylinders and pipes.

Having thus described my invention, what I claim as new, and desire to secure by Letters Patent, is—

1. In a safety device for elevators the combination of an elevator-car movable up and down; inclined guides or ways at opposite 105 sides of the elevator-shaft; guide-blocks carried by the car and coacting with the inclined guides or ways; an air-cylinder provided with a piston and a stem and carried on the car and said pistons coacting with the guide-blocks so that normally at all times when the car is descending the air in the cylinder will 110 be resisting; and a valve on the car to control the escape of air from the air-cylinder during the ordinary descent of the car, for 115 the purpose set forth.

2. In a safety device for elevators the combination of an elevator-car movable up and down; stationary inclined guides or ways; air-cylinders each having a piston and stem 120 and carried on the car; means on the car coacting with the inclined guides or ways; an air-pump carried by the car and provided with means for establishing communication with the air-cylinders; and a valve on the car to 125 control the escape of air from the cylinder to permit the car to descend, for the purpose set forth.

3. In a safety device for elevators the combination of an elevator-car movable up and 130 down; stationary inclined guides or ways at opposite sides of the elevator-shaft; air-cylinders mounted beneath the car one in a plane higher than the other, and each having a pis-

ton and stem; horizontal plates, f' , f^2 , forming a slot or space between the higher and lower cylinders; cross-bars movable in said slot or space and connected with the piston-stems; and guide-blocks mounted on the cross-bars and coacting with the said inclined guides, for the purpose set forth.

4. In a safety device for elevators the combination of an elevator-car movable up and down; stationary inclined guides or ways closer together at the bottom than at the top; one or more air-cylinders, each having a pis-

ton and stem; an air-pump carried by the car to charge the said cylinders with air; guide-blocks on the car which coact with the 15 pistons and the inclined guides or ways; and a valve on the car to control the escape of air from the cylinders for the purpose set forth.

In testimony whereof I affix my signature in the presence of two witnesses.
